UNITED STATES PATENT OFFICE.

ITHAMAR M. JUSTICE, OF DAYTON, OHIO, ASSIGNOR TO THE MANUFACTURERS EQUIPMENT COMPANY, OF DAYTON, OHIO, A CORPORATION OF OHIO.

DRIER FOR CLAY OR CERAMIC PRODUCTS.

1,360,645.

Specification of Letters Patent. Patented Nov. 30, 1920.

Application filed May 3, 1919. Serial No. 294,498.

To all whom it may concern:

Be it known that I, ITHAMAR M. JUSTICE, a citizen of the United States, residing at Dayton, in the county of Montgomery and 5 State of Ohio, have invented certain new and useful Improvements in Driers for Clay or Ceramic Products, of which the following is a specification, reference being had therein to the accompanying drawing.

- 10 This invention relates to driers for clay or ceramic products and has for its particular object to provide an improved drier of the direct action type and, more especially, to provide an improved construction 15 and arrangement of radiated heat driers in which the general movement of the air which carries off the moisture is in the direction in which the product is moved through the kiln.
- 20 Under this arrangement the air for drying enters the drying tunnels at the cold end of the tunnels at normal temperature, becomes heated in its progress through the tunnels and takes up more and more moisture from the wares as the temperature increases, and leaves the product hot and dry at the hot end of the tunnels where the drying operation is completed.

The essential advantage of this method 30 of drying is obtained from the physical fact that the same weight of air can carry an increasing amount of moisture as its temperature is increased. It is a well known physical law that at 42° F. one pound of 35 air will carry .089 oz. of moisture; at 82°, .38 oz.; at 132°, 1.88 oz.; and at 182°, 11.4 oz.

From this known natural law it follows 40 that if the air in a drier operated on this principle leaves the drying tunnel at 162°, the weight necessary to carry one pound of water, if it is saturated, is only 3.1 pounds or 48 $\frac{1}{2}$ cubic feet, as compared with 50 $\frac{1}{2}$ pounds or 689 cubic feet required in a drier 45 operated on the inverse system and working between 82° and 170°. The carrying power of air increases so rapidly with the rise in temperature that in practice in the construction and operation of driers of this type it 50 is not usual to make the air issue saturated at the hot end of the tunnels. If this were done, the drying would be extremely slow at the beginning and very rapid at the end of the operation.

As applied in the present invention, a 55 most effective method of drying is obtained. There is a combination of powerful heating and radiating influences, which, together with the principle of direct action, produces highly satisfactory results. The 60 moisture carrying power of the air increases so rapidly with the increase in temperature that there is no danger of condensation on the ware and the drying time is shortened and fuel requirements reduced very mate- 65 rially.

With driers of my improved construction most clays, including the more delicate or tender grades, may be dried in the comparatively short time of thirty hours. During 70 the greater part of the operation the air is so charged with moisture as to be nearly saturated. Strong air currents and excessive surface drying are therefore avoided, and many clays which inevitably crack when 75 dried in other ways may be successfully treated by my improved construction and process of treatment.

In the general construction, including the arrangement of the fuel pits and tunnels 80 and the drying tunnels, my improved drier is similar to my improved drier of the inverse type, which is well known on the market, being used extensively in the manufacture of various kinds of ceramic products, but differs from my earlier constructions fundamentally in that the air for carrying off the moisture passes through the 85 drier tunnels in the same direction the product is moving, as distinguished from the old 90 construction in which the movement is inverse.

Driers of this type are usually of large capacity made up of a plurality of fuel and drier tunnel units, all constructed and operated in the same way and all served by a common stack. Only one such unit is here shown to illustrate a construction in which my invention has been applied, it being understood that the construction of the different units that make up the drier as a 95 whole is essentially the same.

As shown in the accompanying drawings:-

Figure 1 is a longitudinal sectional view 105 of the direct radiated heat type drier in which the present invention has been applied.

Fig. 2 is a cross sectional view taken on the line 2—2 of Fig. 1, and looking in the direction of the arrows.

Fig. 3 is a cross sectional view taken on the line 3—3 of Fig. 1, having the upper portion of the stack broken away.

Fig. 4 is a plan view in cross section of the receiving end of the drier taken on the line 4—4 of Fig. 3.

Fig. 5 is an enlarged detailed plan view taken on the line 5—5 of Fig. 1; and

Fig. 6 is an enlarged detailed view in elevation of the upper portion of one of the heat flues.

It will be observed that the fuel tunnels 1 and drier tunnels 2 extend longitudinally the entire length of the structure, the first section of the fuel tunnels consisting, as here shown, of the usual fuel pit 3, fire box 4, bag wall 5, and baffle wall 6. This part of the construction may be of any suitable type, the arrangement here shown being for illustration purposes only.

The opposite end of the tunnel 1 leads into a transverse tunnel 7, which is divided into sections by cross walls 8. The roofs of the tunnels are formed by the metal arches 9 and the different units are spaced apart by longitudinal base walls 10, the upper portion of the walls 11 extending above the arches 9 to the ceiling wall 12, and beyond the ceiling wall to the roof 13 and serving to separate the different units of the structure. As seen in Fig. 5, the walls 11 are jogged to one side when they reach a point above the ceiling of the drying chambers. This jog is formed in order not to close the upper ends of the flues 14 and yet to permit of the continuation of the walls 11 on up to the roof to support it.

As best shown in Figs. 2 and 4 of the drawings, each of the sectional tunnels 7 is provided with a flue 14 which extends upwardly through the wall 11 and opens into the draft channels 15 leading to the stack 16.

The air for carrying off the moisture from the product treated in the drying tunnels is introduced through an air pit 17, immediately adjacent the receiving ends of the tunnels, thence through an aperture 18 in the end wall of the structure and an air duct 19 direct into the drying tunnels. The opening to the air pit is normally covered or closed by a suitable grate or trap door 20, and the entrance to the drying tunnels is normally closed by a suitable metal door 21.

At the delivering end of the drying tunnels the ceiling walls are provided with draft apertures 22 opening into air channels 23 leading directly into stack 16, a wall 24 serving to separate the air channels from the flue channels 15, the latter leading into the stack through an offset extension 25 thereof.

A track 26 is laid on the floor of the drier tunnels in any suitable manner, and extends

outwardly beyond the receiving entrance and also beyond the delivering end of the tunnels, as shown in Fig. 1 of the drawings. The ware is moved through the tunnels on suitable trucks supported upon track 26, the loaded trucks being advanced step by step as the drying operation progresses.

From the foregoing detailed description the construction and operation of my improved driers will be readily understood. While the principle of introducing the air through the drying tunnels in the same direction ware is moved through them, is not new *per se* as applied in the present construction, the improved construction is nevertheless essentially different from what has been the practice heretofore, and decided improvements are obtained in the results of operation in the quality of the ware produced and in the economy and general facility of production.

It will be understood from the illustrations of the drawings and the foregoing description that the drying tunnels are heated throughout their length by the fuel tunnels underneath, the drying space at the delivery ends of the tunnels, which are immediately above the furnaces, being, of course, much hotter than at the receiving ends of the tunnels.

It will also be observed that the hot air passing upwardly from the fuel tunnels into the draft channels leading to the stack serves to keep the ceiling wall of the drier tunnels heated; also that the air channels leading from the delivery ends of the furnace, through which the hot, moisture laden air from the tunnels passes to the stack, serve to keep the ceiling wall at that end of the tunnels heated, so that an even temperature throughout the drying space is maintained and the drying operation is thereby greatly facilitated and its increased effectiveness results in material improvement in quantity and quality production.

The air temperatures of the drying tunnels may, of course, be varied to suit the ware receiving treatment. In practice, the air is introduced to the tunnels at normal atmospheric temperature and gradually increases in temperature as it moves toward the hot end of the tunnels where a temperature of about 200° F. is usually maintained in treating the usual grades of clay.

It will be understood that the air as it passes through the tunnels may at all temperatures be saturated, or nearly saturated, and that its moisture carrying capacity will be constantly increased with the increase in temperature, and that the drying operation becomes increasingly faster toward the hot end of the tunnels.

The gain in efficiency of my improved direct action drier, as here shown, as compared to driers of the ordinary inverse type, en-

ters decisively into the economy in production of clay products. The saving effected in the time required for the completion of the drying operation, over the old method of 5 drying, is very material; reduction in fuel required may be conservatively estimated at 20 to 25%; and the substantial loss of finished product due to cracking, resulting from air drafts or sudden changes in drying 10 temperatures, under the old practice is practically eliminated in the new construction and operation.

Having thus fully described my invention, what I claim as new and desire to secure by 15 Letters Patent, is:—

1. In a drier for ceramic products the combination with drying tunnels having receiving and delivering ends, means for moving the product through said tunnels, fuel tunnels 20 extending beneath the drying tunnels, a stack located intermediate the ends of said tunnels, channels leading from the fuel tunnels and the drying tunnels, respectively, to said stack, and means to introduce air to 25 the drying tunnels at the receiving ends thereof, whereby the temperature of said air will be gradually increased as it passes through the tunnels.

2. In a drier for ceramic products the combination with drying tunnels having receiving and delivering ends, means for moving the product through said tunnels, fuel tunnels extending beneath the drying tunnels from the delivering to the receiving ends 30 thereof, a stack communicating with said tunnels, channels extending in opposite directions from the fuel tunnels and the drying tunnels, respectively, to said stack, and means to introduce air at atmospheric tem- 35 perature to the drying tunnels at the receiving ends thereof, whereby the temperature of said air will be gradually increased as it passes through the tunnels.

3. In a drier for ceramic products, the combination, with drying tunnels having receiving and delivering ends, means for moving the product through said tunnels, fuel tunnels extending beneath the drying tunnels, a stack connected to the fuel tunnels, 50 channels communicating with the stack and with the drying tunnels, and air inlets for the receiving ends of the drying tunnels, whereby air introduced into the drying tunnels at the receiving ends thereof will be 55 gradually increased in temperature as it passes through the drying tunnels.

4. In a drier for ceramic products the combination with drying tunnels having receiving and delivering ends, means for moving the product through said tunnels, fuel tunnels extending beneath the drying tunnels from the delivering to the receiving ends thereof cross tunnels communicating with the fuel tunnels, and a stack and oppositely 60

extending channels communicating with the 65 drying tunnels and said cross tunnels, whereby air introduced into the drying tunnels at the receiving ends thereof will be gradually increased in temperature as it passes therethrough.

5. In a drier for ceramic products the combination with drying tunnels having receiving and delivering ends, means for moving the product through said tunnels, fuel tunnels extending beneath the drying tunnels 70 from the delivering to the receiving ends thereof, cross tunnels having flues, a stack and channels communicating with the drying tunnels and the flues of the cross tunnels, whereby air introduced into the drying 75 tunnels at the receiving ends thereof will be gradually increased in temperature as it passes therethrough.

6. In a drier for ceramic products the combination with drying tunnels having receiving and delivering ends, means for moving the product through said tunnels, fuel tunnels extending beneath the drying tunnels, a stack and opposite channels leading thereto respectively from the fuel and drying tunnels, whereby air introduced into the 80 drying tunnels at the receiving ends thereof will be gradually increased in temperature as it passes therethrough.

7. In a drier for ceramic products the combination with drying tunnels having receiving and delivering ends, means for moving the product through said tunnels, fuel tunnels extending beneath the drying tunnels, a stack located intermediate the ends 95 of said tunnels and channels communicating with said stack and the fuel and drying tunnels, respectively, whereby the temperature of said air will be gradually increased 100 as it passes through the tunnels.

8. In a drier for ceramic products the combination with drying tunnels having receiving and delivering ends, means for moving the product through said tunnels, fuel tunnels extending beneath the drying tunnels, a stack located intermediate the ends 110 of said tunnels and channels communicating with said stack and the fuel and drying tunnels, respectively, and extending over the drying tunnels, whereby the temperature of said air will be gradually increased 115 as it passes through the tunnels.

9. In a drier for ceramic products the combination with drying tunnels having receiving and delivering ends, means for moving the product through said tunnels, fuel tunnels extending beneath the drying tunnels, a stack located intermediate the ends 120 of said tunnels and channels communicating with said stack and the fuel and drying tunnels, respectively, extending over and parallel to the drying tunnels from said opposite ends, whereby air introduced into the 125

drying tunnels at the receiving ends thereof will be gradually increased in temperature as it passes therethrough.

10. In a drier for ceramic products the combination with drying tunnels having receiving and delivering ends, means for moving the product through said tunnels, fuel tunnels extending beneath the drying tunnels longitudinally therewith, sectional cross tunnels divided by cross walls, and communicating with the fuel tunnels, and a stack communicating with the drying tunnels and said cross tunnels, whereby air introduced into the drying tunnels at the receiving ends thereof will be gradually increased in temperature as it passes therethrough.
11. In a drier for ceramic products the

combination with drying tunnels having receiving and delivering ends, means for moving the product through said tunnels, fuel tunnels extending beneath the drying tunnels longitudinally therewith, sectional cross tunnels divided by cross walls, and communicating with the fuel tunnels, and air pits and air passages leading therefrom into the receiving ends of the drying tunnels, whereby air at atmospheric temperature may be introduced thereto, a stack communicating with the drying tunnels and said cross tunnels, whereby air introduced into the drying tunnels at the receiving ends thereof will be gradually increased in temperature as it passes therethrough.

In testimony whereof I affix my signature. 35

ITHAMAR M. JUSTICE.
